UNITED STATES PATENT OFFICE.

ANDREW HESJEDAL, OF FERTILE, MINNESOTA.

WIRE-STRETCHER.

1,320,856.

Specification of Letters Patent.

Patented Nov. 4, 1919.

Application filed November 13, 1918. Serial No. 262,411.

To all whom it may concern:

Be it known that I, ANDREW HESJEDAL, a citizen of the United States, residing at Fertile, in the county of Polk and State of Minnesota, have invented certain new and useful Improvements in Wire-Stretchers, of which the following is a specification.

This invention has relation to wire stretchers, and the nature and objects thereof will 10 be readily apparent to those skilled in the art to which it appertains in the light of the following explanation of the accompanying drawings, illustrating what I now believe to be the preferred embodiment, or mechanical 15 expression, of my invention from among other forms and arrangements within the spirit thereof, and the scope of the appended claims.

However, an object of the invention is to 20 provide a wire stretcher of new and novel form, whereby a strand of wire may be pulled to take up the slack between posts, and subsequently to place said strand under tension before stapling the wire to the post.

Another object of the invention is to provide a wire stretcher of the character set 25 forth which is readily portable, and which may be quickly associated with a fence post or the like when a wire is to be stretched.

In addition to the foregoing, my invention 30 comprehends improvements in the details of construction and arrangement of parts to be hereinafter more fully described and particularly pointed out in the appended claims.

In the accompanying drawings, in which 35 similar and corresponding parts are designated by the same characters of reference throughout the several views in which they appear:

Figure 1, is a view in side elevation of a 40 wire stretcher constructed after the fashion of my invention, and

Fig. 2, is a view thereof in plan.

With reference to the drawings, 1 indicates 45 a frame comprising horizontal frame bars spaced transversely and connected at their terminals, one of said transverse connecting members 2 being concaved for a purpose to be presently noted. The longitudinal frame bars 1 are provided at their intermediate portions with enlargements 3, apertured transversely to receive a shaft 4 forming a support for the wire stretcher mechanism to be presently described. Extending 50 upwardly from the said enlarged portion 3 there are provided integrally

formed frame extensions 5, in the form of vertical frame bars directed toward each other at their upper terminals and connected by means of a latch 6, which is pivoted to 60 one of the terminals and has detachable connection with the opposite terminal. Within the frame members 1 and 5, there is provided a wheel 7 mounted upon the shaft 4 and fixed thereto for rotation. Said 65 wheel 7 is formed with a peripheral groove 8, and the shaft 4 is further provided with a ratchet wheel 9, adapted for rotation with said shaft. The ratchet wheel 9 is located within the frame and a pawl 10, pivoted 70 to one of the longitudinal frame members at 11 is urged by gravity into a position to engage the periphery of the ratchet wheel. The shaft 4 is extended beyond the frame at the side of the ratchet wheel to receive a 75 crank arm which is secured to the shaft.

Disposed around the wheel in uniformly circumferentially spaced relation, are automatically operable wire engaging clamp devices indicated generally at 13. The devices are identical in construction and a description of one will suffice for all. Said devices are comprised of clamping elements or members 14. Crossed at points adjacent their outer terminals and pivoted at said 80 point of intersection between ears 15 located at the central portion and bottom of the peripheral groove 8 of the wheel 7, an opening is provided in the wheel between each of the ears 13, said opening extending 85 approximately radially to receive the opposite ends of the members 14, which are curved and extended laterally without the face of the wheel 8 at either side, in a direction at substantially right-angles to said 90 face, as indicated at 16. The outer terminals of each of the members 14 extended beyond the side faces of the wheel, are provided with heads 17 having arcuate outer faces. The arcuate heads 17 are each arranged at the same radial distance from the center of the wheel, and during rotation of 100 said wheel are engaged by an arcuate cam plate 18, one of which is provided at either side of the wheel and secured to the upright member 5 and to the longitudinal members 1 by means of a vertical strap 19. In operation, the device is placed with the concave portion 2 at one end of the frame against the fence post or the like and the wire to 105 be stretched is brought into proper relation with the mechanism by disengaging the

55

latch 6 so as to open the upper portion of the frame 5 and permit the insertion through said opening of the wire. The wire is then engaged in the uppermost one 5 of the clamping member by inserting the wire between the clamping jaws 14. The handle 12 is then rotated, and as the arcuate heads of the clamping member in which the wire has been inserted and brought into 10 engagement with the cam plate 18 said arcuate head is moved inward simultaneously and toward the wheel, thereby bringing the projecting terminals of said clamping member together upon the wire. Continued rotation 15 of the handle rotates the wheel, thereby stretching the wire, until the next adjacent clamp is brought beneath the wire for engagement therewith. Continued rotation of the wheel, clamps the second clamping 20 device upon the wire, and the pulling strain upon the wire is continued. This operation is repeated automatically by merely turning the crank handle 12, until all the slack of the wire has been taken up. Additional turning 25 of the handle will produce the requisite tension upon the wire and said wire is then stapled or otherwise secured to the fence post. The device may be readily held against the fence post, as the strain of the 30 wire is extended longitudinally through the main frame, thereby holding the frame even tighter against the fence post. After the stretching operation has been completed, the wire stretcher may be readily disengaged from the post and carried about by 35 means of the handle portion or frame portion 5. The engagement of the pawl 10 with the ratchet wheel 9, precludes any backward movement of the wheel, and retains 40 the wire under tension until it has been secured to the post.

While I have illustrated and described my invention with some degree of particularity, I realize that in practice various alterations 45 thereover may be made, and I therefore reserve the right and privilege of changing the form of the details of construction or otherwise altering the arrangement of the co-related parts without departing from the 50 spirit of the invention or the scope of the appended claims.

Copies of this patent may be obtained for five cents each, by addressing the "Commissioner of Patents, Washington, D. C."

Having thus described my invention what I claim as new and desire to secure by Letters Patent is:

1. A wire stretcher including a frame 55 comprising horizontal side bars spaced transversely, a wheel rotatably mounted between said side bars, means thereon for engagement with a strand of wire, said side bars intermediate their ends each being provided with vertical bars directed toward each other at their upper terminals, and a latch connecting said terminals whereby a wire may be passed between the upper terminals when the latch is open or whereby the device may be carried by the vertical bars when the latch is closed.

2. A wire stretcher including a frame, a wheel mounted for rotation therein and having its periphery provided with a plurality of circumferentially arranged radial openings, a pair of oppositely disposed ears around each opening, a plurality of wire engaging devices mounted upon the periphery of the wheel, each device comprising 70 a pair of crossed members pivoted together and to said ears to form movable jaws passing through said openings in the wheel and having arcuate handle portions arranged within the wheel to extend in opposite directions through the wheel a substantial distance beyond the outer faces thereof, heads secured to the extended portion of the handle portions and having arcuate faces, and cam plates stationarily mounted upon 75 the frame in the path of movement of the heads, whereby when said wheel is rotated said arcuate faces of said heads are engaged by the cam plates and the relatively movable jaws of each device separately brought together into engagement with the wire to stretch the same during peripheral movement of said devices, said devices becoming 80 automatically disengaged from the wire when the heads of the handle portions disengage the cam plates.

In testimony whereof I affix my signature in presence of two witnesses.

ANDREW HESJEDAL.
